UNITED STATES PATENT OFFICE.

BENJAMIN E. HORTON, OF SYRACUSE, NEW YORK.

AUTOMOBILE HEADLIGHT.

Application filed February 20, 1922. Serial No. 537,924.

To all whom it may concern:

Be it known that I, BENJAMIN E. HORTON, a citizen of the United States, residing at Syracuse, in the county of Onondaga and 5 State of New York, have invented certain new and useful Improvements in Automobile Headlights, of which the following is a specification.

This invention relates to improvements in 10 electric headlights for motor and other vehicles, and has for its object to provide a lamp structure which includes two electric lamps, one of low and the other of high candle power, the said lights being disposed 15 in separate compartments. A further object is to provide means for dimming one of said lights while the vehicle is being driven around the city streets or standing still. And a further object is to provide 20 means for preventing the glare from the high power light from blinding pedestrians and the drivers of other vehicles while approaching the headlights.

I attain these objects by the means set 25 forth in the detailed description which follows, and as illustrated by the accompanying drawing, in which—

Figure 1 is a front face view of the head-light, to which my improvement is applied. 30 Fig. 2 is a central vertical section taken on line 2—2 of Fig. 1, Fig. 3 is a front elevation of the opaque shield. Fig. 4 is a side elevation of the same. And Fig. 5 is a horizontal section taken substantially on line 35 5—5 of Fig. 1.

In the drawing, 2 represents the outer casing or shell in which are disposed the several parts which constitute the head-light, the forward open end of the casing being flared 40 and partially closed by a detachable annular cap 3. 4 represents the usual circular transparent glass or lens, which is supported inside of the cap 3. 5 is the usual conical reflector which is disposed concentrically in 45 the casing 2, its flaring open end 5' registering with the lens-covered opening in the cap 3. The rear closed end of the reflector supports a high-power electric lamp 6, which is supplied with current by wires 6'. The 50 lamp 6 is preferably disposed in the line of the longitudinal axis of the reflector, as shown in Figs. 1, 2 and 5. 7 represents a low candle power lamp, which is disposed directly above the lamp 6, and is supplied 55 with current by wires 7'.

My improvement consists of a sheet metal

or other suitable opaque member 8, which is substantially L-shaped in side elevation, as shown in Figs. 2 and 4, the arms 8' and 8^a thereof being substantially semi-circular 60 for conforming to the curvature of the cap 3 and the reflector 5. When the member 8 is placed in the head-light, its horizontal arm 8' is disposed between the lights 6 and 7, thereby dividing the interior of the reflector 5 into upper and lower compartments 5^a and 5^b. The upright arm 8' of the device, hereinafter referred to as the dimmer, is preferably disposed parallel to and bears against the inner top surface of the lens, and substantially closes the forward end of the compartment 5^a, as best seen in Figs 1 and 2. In order to provide for the emission of light from the lamp 7, the dimmer 8' is perforated at 8^b, the said perforation being 75 in the line of the vertical axis of the reflector and lamps 6 and 7 and preferably being disposed directly in front of the lamp 7, as best seen in Figs 1 and 2. By this construction and arrangement a portion of the 80 light from the lamp 7 shines through the perforation 8^b, and serves as a pilot light when the car is standing still, and at the same time the lamp 7 performs the functions of the usual low-power or dimmed head-light, 85 when the vehicle is being driven about the lighted city streets. The perforation 8^b is preferably formed by a shearing-die, which first stamps out a substantially disk-shaped tongue 8^c, and then shears the metal 90 below said perforation for providing a relatively narrow flexible stem or neck 8^d, which is afterwards bent downwardly for providing an integral depending glare-stop, whose axis corresponds to the horizontal axis of 95 the lamp 6, as best seen in Figs. 1, 2, 3 and 4. The glare-stop 8^e, which is a permanent fixture and requires no operation is preferably disposed in the same transverse vertical plane as the dimmer 8', and being disposed directly in front of the lamp 6, prevents the dazzle or glare of the said lamp from blinding or otherwise inconveniencing persons approaching a vehicle upon which my head-lights are installed. The under- 100 side of the horizontal arm 8^a is preferably silver-plated and polished and serves as a reflector, the same as the inner surface of the part 5. This horizontal reflector 8^a preferably inclines upwardly slightly as it extends rearwardly, and therefore tends to direct the reflected rays of light downwardly, 105

intensifying the illumination of the roadway directly in front of the vehicle. The member 8 is preferably detachably applied to the lens 4, by means of integral lugs 5 or clips 8^e, which are clinched to the opposite margins of the lens, as best seen in Figs. 2 and 5.

My entire improvement, which comprises the dimmer 8', the plane reflector 8^a, and the 10 glare-stop 8^c, is made from a single piece of sheet metal, which may be produced at slight cost, and the said improvement may be readily, quickly and conveniently installed in any style or make of head-lights, 15 without requiring any alteration or change in the construction and arrangement of the said lights.

Having thus described my invention, what I claim, is—
20 1. A head-light, including a hollow conical reflector, a lens closing the flaring end of said reflector, an L-shaped opaque member, the horizontal arm of said member dividing said reflector into upper and lower 25 compartments, the vertical arm of said member substantially closing the forward end of the uppermost compartment and having a perforation, an electric lamp disposed in the upper compartment in line with said 30 perforation, an electric lamp disposed in the lower compartment, and a disk-shaped tongue depending from the vertical arm and shielding the lamp in the lowermost compartment.
35 2. In a head-light, an outer casing, a lens closing the open end of said casing, a hollow conical reflector disposed in said casing, an opaque member having a horizontal arm which divides the interior of the reflector

into upper and lower compartments and 40 having a vertical arm for closing the forward end of the upper compartment, said vertical arm having a circular opening, and an integral disk-shaped tongue bent downwardly for providing a pending glare-stop 45 whose center corresponds to the longitudinal axis of the said reflector, an electric lamp of high candle power disposed in the line of said longitudinal axis, and an electric lamp of lower candle power disposed 50 in the upper compartment and registering with said circular opening, and means for detachably securing said member to said lens.

3. A headlight, including a hollow conical 55 casing, a hollow conical reflector disposed in said casing, the corresponding ends of said parts being open, a lens closing the open end of the reflector, an L-shaped opaque member disposed between said lens and said 60 reflector having a horizontal arm which divides the interior of the reflector into upper and lower compartments, and having a vertical arm disposed parallel to the lens and closing the forward end of the uppermost 65 compartment, said vertical arm having a central perforation for the emission of a dim light, an electric lamp disposed in the upper compartment, an electric lamp disposed in the lowermost compartment substantially in the line of the longitudinal axis of said reflector, and a disk-shaped tongue depending from and disposed in the 70 same plane as said vertical arm adapted to stop the glare from the lamp in the lowermost compartment.

In testimony whereof I affix my signature.
BENJAMIN E. HORTON.
